CLAIM

The ornamental design for a chest, as shown and described.

DESCRIPTION

FIG. 1 is a front elevational view of a chest showing my new design;

FIG. 2 is a top plan view thereof;

FIG. 3 is a right side elevational view, the left side being a mirror image thereof;

FIG. 4 is a bottom plan view thereof;

FIG. 5 is a front elevational view of a second embodiment of the chest shown in FIG. 1;

FIG. 6 is a greatly enlarged detail view taken in vertical section along line 6—6 of FIG. 1;

FIG. 7 is a greatly enlarged detail view taken in horizontal section along line 7 —7 of FIG. 1;

FIG. 8 is a greatly enlarged detailed view taken in vertical section along line 8—8 of FIG. 1; and,

FIG. 9 is an enlarged detail view taken in horizontal section along line 9—9 of FIG. 1.

The top, bottom and side elevational views of the chest of FIG. 5 are identical to those of FIG. 1 except for height and width. The rear of each of the chests of FIGS. 1 and 5 is plain and unornamented.
